[57] **ABSTRACT**

An apparatus for the after-treatment of exposed sheet material comprising a trough, a tiltable perforated feed table mounted above said trough, a working table adjoining said feed table, and a developing container positioned laterally below the feed table and being inclined with respect to the horizontal.

APPARATUS FOR THE AFTER-TREATMENT OF EXPOSED SHEET MATERIAL

This invention relates to an apparatus for developing, rinsing, correcting, and, if desired, fixing exposed sheet material.

It is known to develop exposed sheet material, e.g. printing plates, in containers. Such a container generally has the form of a vertical or slightly inclined narrow trough into which a plateholder is manually or mechanically introduced and, after a certain developing time, removed again. Such containers permit the performance of developing as an immersion process and thus undoubtedly represent an improvement over conventional apparatus in which the developer liquid is applied to the plate manually by means of a sponge or the like. Plates are difficult to handle at larger plate sizes and, furthermore, there is the disadvantage that rinsing off the excessive developer and the subsequent correcting treatment must be performed by means of separate devices, which requires additional conveying operations.

In order to overcome this drawback, automatic developing devices have been constructed in which the exposed plates are laid onto a conveying belt which conveys them past rotating brushes applying the developer, then to rinsing and drying stations, then to the correcting table and, if desired, to further after-treatment stations, e.g. a fixing station. Such machines, however, have not found practical use, primarily because of their high price, but also because of their large size and their high developer consumption, resulting from the relatively rapid oxidative decomposition due to foaming at the brushes.

The present invention provides an apparatus by means of which the treatment steps can be performed as economically as possible, with as little space as possible, and with as little effort as possible.

In accordance with the invention, this is achieved by an apparatus for the after-treatment of exposed sheet material which includes a trough covered by a fixable, perforated feeding table tiltable about a point of rotation, a laterally adjoining working table, and a developing container arranged laterally beneath the feeding table and inclined at an angle with respect to the horizontal.

The feeding table, working table, and developing container preferably are so arranged that the feeding table in the horizontal position is in alignment with the working table and, in the tilted position, in alignment with the container. In this case, it is sufficient to provide arresting means only for the two end positions of the feeding table, e.g. in the form of a rod arranged in the trough and a hinged support at the bottom side of the feeding table.

Occasionally, e.g. in the treatment of thin material having a sagging tendency, it may be of advantage to select the tipping angle for the feeding table smaller than the inclination angle of the developing container. Under certain circumstances, the end of the plate to be developed is even bent to such an extent when leaving the feeding table that, for easy immersion of the plate into the container, the feeding table need not be tilted at all.

In a preferred, particularly compact construction, the developing container is so arranged beneath the

working table that working in two planes is assured. Wherever it is recommended for the working operation, the container, of course, also may be placed on the side of the feeding table away from the working table.

For the angle at which the container is inclined with respect to the horizontal, values between 10° and 25°, particularly between 12° and 18°, have proved suitable.

The interior of the container preferably is provided with a movable support onto which the plate to be developed is placed and by means of which it is kept at a sufficient distance from the container walls during development. For this purpose, the support may be guided in rails, for example, and/or may be provided with spacers. Furthermore, the upper end of the support advantageously is provided with a handle which is not immersed in the developing liquid and by means of which the support can be lifted out of the container after the time of developing; in this manner, the plate can be gripped outside the developer liquid and removed from the bath in a simple and clean manner.

Introducing the plate into the container, removing it therefrom, passing it onto the perforated feeding table, and therefrom onto the working table, in the simplest case, may be performed manually; this is even possible in the case of large plate sizes without excessive expenditure of force since the container is only slightly inclined with respect to the horizontal. However, gripping devices and mechanical moving means may be employed which permit the mechanical performance of the individual conveying steps.

If the container is to be kept closed during the developing process or in the unused but filled state, the upper end thereof is provided with a cover which may be arranged, e.g., at the bottom of the container and is of such a shape that it is kept closed by a steplike slightly angular lateral projection of the feeding table in the horizontal position. It is swung open by the tipping thereof, by means of its own weight, and is so placed into the steplike projection of the feeding table that a smooth transition between the feeding table and the plateholder in the container is assured.

In a preferred embodiment, the container is furthermore provided with a lower outlet for the developing liquid, which is connected with a pump. This pump may be either placed beneath the container or elsewhere and permits complete removal of the depleted developing solution from the container also in those cases where an outlet above the discharge level is to be used. When using a pump which can be changed from suction to pressure operation, it is possible, of course, to also pass fresh developer solution through the outlet and to dispense with filling from above.

In the interest of a working procedure occupying as little space as possible, it has proved advantageous to provide the trough with a rinsing device which, for example, may be a hand spraying device. It serves for washing away the developer solution superficially adhering to the plate after removal from the container, and it serves also for cleaning a plate which was subjected on the working table to further treatments, e.g. to fixation often usual after development, or to providing it with a protective color. The washing steps are best performed while the plate lies on the perforated feeding table in the horizontal position so that the

washing water flows off through the preferably circular or slitshaped perforations.

It is of advantage to provide the trough at the bottom or at another suitable place with a discharge aperture so that the washing liquor does not accumulate in the interior of the trough but flows off or, if required, can be pumped off.

On the working table, the correction of the plate is particularly performed. If desired, there may be a curtain between the feeding table and the working table which prevents sprinkling of the working table by the washing device.

In another embodiment of the apparatus of the invention, the working table is provided with a movable lateral arm support. Furthermore, the working table may be so constructed that it can be inclined in the direction towards an operator. If desired, the arm support also may be inclinable.

The apparatus of the invention and its function are further illustrated in the following by way of one embodiment shown in the accompanying drawings.

The FIGURE illustrates an embodiment of the invention.

A trough 1 provided with a discharge aperture 16, a water connection 18, and a rinsing device 17 connected therewith has a cover consisting of a fixable, perforated feeding table 3 tilttable about a point of rotation 2. Laterally adjoining this table, there is a working table 19, having a movable arm support 20. The feeding table 3 has a steplike slightly angular lateral projection 4. The arresting means of the feeding table 3 are the rod 5 in the trough as well as the hinged support 6 at the bottom of the feeding table. Beneath the working table 19, there is a developing container 7 tilted through an angle α with respect to the horizontal, which container is provided with a cover 8 and an outlet 14 for the developer solution 13. The interior of the container contains an exposed plate 12 on a movable support 9 which is conveyed by spacers 10 and 10' and has a handle 11 at its upper end. The outlet is connected with a pump 15 for replenishing the developer solution.

In the simplest case, the working procedure with the use of this apparatus is as follows: The exposed plate 12 is placed onto the perforated feeding table 3 in the horizontal position and, after the tipping thereof and simultaneous swinging open of the cover 8, conveyed onto the support 9 which is in the container 7 provided with the developer solution 13. As soon as the plate has passed the cover, the latter is closed by returning the feeding table into the horizontal position. After the desired developing period, the cover is opened, by again tipping the feeding table, and the support is removed from the container to such an extent that the plate placed thereon can be drawn out and onto the feeding table. After the feeding table has been returned to the horizontal position, the developed plate is rinsed, the desired further treatments of the plate are performed, and the plate is pushed onto the working table 19 for correction.

The apparatus of the invention, of course, is not limited to this embodiment. If desired, it is particularly possible without great expenditure to add a fixing station to the working stations. This may be performed, for example, by providing another container on the opposite side of the perforated feeding table beside the working table, which is likewise slightly inclined and receives the plate after the correcting treatment. It is also possible, however, that such a container is so arranged that it is beneath the developing container or symmetrical thereto on the other side of the perforated feeding table which, in this case, must be tiltable in both directions. Also a device suitable for drying the developed and rinsed or the completely fixed plate, such as a warm air blower device, of course, may be provided in the zone of the trough, if it is desired in the individual case.

It will be obvious to those skilled in the art that many modifications may be made within the scope of the present invention without departing from the spirit thereof, and the invention includes all such modifications.

What is claimed is:

1. An apparatus for the after-treatment of exposed sheet material comprising a trough, a tiltable perforated feed table mounted in said trough, a working table adjoining said feed table, and a developing container positioned laterally below the feed table and being inclined with respect to the horizontal, said feed table in the horizontal position being in alignment with the working table and, in the tilted position, being in alignment with the developing container.
2. Apparatus according to claim 1 in which the developing container is positioned beneath the working table.
3. Apparatus according to claim 1 in which the developing container is inclined at an angle between 10° and 25°.
4. Apparatus according to claim 1 in which the developing container is provided with removable supporting means for the exposed sheet material.
5. Apparatus according to claim 4 in which the supporting means has a handle at the upper end thereof and spacers on the bottom thereof.
6. Apparatus according to claim 1 in which the developing container has an outlet for developer solution and a pivotally mounted cover.
7. An apparatus according to claim 6 in which the feed table has a steplike, slightly angular projection thereon for receiving the pivotally mounted cover.
8. An apparatus according to claim 6 including pump means connected to the outlet.
9. Apparatus according to claim 1 including rinsing means positioned adjacent said trough.
10. Apparatus according to claim 1 including discharge means at the bottom of said trough.
11. Apparatus according to claim 1 in which the working table has a lateral movable arm support.
12. Apparatus according to claim 1 in which the working table is inclinable.
